UNITED STATES PATENT OFFICE

162,047

MICROSCOPE ILLUMINATOR

Howard Lindemann, Great Neck, N. Y.

Application November 16, 1950, Serial No. 13,008

Term of patent 7 years

(Cl. D57—1)

To all whom it may concern:

Be it known that I, Howard Lindemann, a citizen of the United States, residing in Great Neck, L. I., New York, have invented a new, original, and ornamental Design for a Microscope Illuminator, of which the following is a specification, reference being had to the accompanying drawings, forming a part hereof.

Fig. 1 is a front and side perspective view of a microscope illuminator embodying my new design.

Fig. 2 is a rear and side perspective view thereof.

Fig. 3 is a top plan view.

I claim:

The ornamental design for a microscope illuminator, as shown.

HOWARD LINDEMANN.
